UNITED STATES PATENT OFFICE.

ARTHUR A. HILL, OF NEW YORK, N. Y.

ANTISLIPPING ATTACHMENT FOR HORSESHOES.

No. 918,853.

Specification of Letters Patent.

Patented April 20, 1909.

Application filed July 25, 1908. Serial No. 445,335.

To all whom it may concern:

Be it known that I, ARTHUR A. HILL, a citizen of the United States, residing at the city of New York, in the borough of Bronx 5 and State of New York, have invented certain new and useful Improvements in Anti-slipping Attachments for Horseshoes, of which the following is a full, clear, and exact description.

10 My invention relates to horse-shoes, and more particularly to an anti-slipping device or attachment therefor.

The object of the invention is to provide an anti-slipping attachment of such construction that it may be readily applied to and removed from an ordinary horseshoe and be firmly secured thereto in use, so that there is no danger of its accidental separation or detachment. With this general purpose 15 in view, I provide an attachment in two independent sections adapted to be secured on the two sides or members of an ordinary horse-shoe, and which have integral or rigid hooks or prongs at their extremities to engage over the toe and heel of the shoe to resist any direct withdrawal strains. Coöperating with these hooks or prongs I provide means to prevent lateral displacement of the anti-slipping devices on the shoe, and which 20 maintain the hooks or prongs in their positions of effective engagement. The means for preventing lateral displacement of the anti-slipping device sections are of such a character that each of the latter may be 25 conveniently removed when desired, by simply unscrewing a nut or similar device.

The above construction of the anti-slipping attachment in two separate halves or sections insures a more accurate fit on a 30 slightly worn shoe, and also permits a certain adaptability or range of adjustment to shoes of varying forms and sizes.

With the above and other objects in view, my invention consists in the features of construction and combination as hereinafter set forth and claimed.

In the drawings: Figure 1 is a bottom plan view of an anti-slipping device or attachment embodying the principles of my invention. Fig. 2 is a side elevation of the same. Fig. 3 is a top plan view of one of the separable sections, and Fig. 4 is a sectional view on the line IV—IV of Fig. 1.

Referring to the drawings, in which like 55 parts are designated by the same reference sign, 1 indicates the two halves or sections of

the anti-slipping device or attachment, and which are similar in all respects, except that they are adapted for the right and left hand sides of a shoe respectively. Each has a 60 curved outline, corresponding to the shape of half of an ordinary horse-shoe, and at one end 2, corresponding to the toe of the shoe, there is formed an integral hook or prong 3 which is bent inward or under-cut so as to 65 engage over the usual toe, which may be also under-cut or filed away to give a proper fastening engagement. 4 designates prongs on the other ends of the respective sections of the anti-slipping attachment, and corresponding to the heel extremities of the horse-shoe. Each of these prongs or hooks 4 is bent or under-cut in a manner corresponding to the prongs or hooks 3, so as to engage 70 over the heel portions of the shoe. The 75 shoe may be filed away or under-cut at its heel portions to accommodate the hooks or prongs 4.

Each section 1 of the anti-slipping attachment has a lug or ear 5 on its outside edge, 80 and which projects inwardly so as to engage the side of a shoe. The inside edges of the sections are, however, unprovided with any corresponding ears or lugs, so that the sections are adapted to be slid sidewise into 85 place upon the shoe from its respective sides. In this manipulation the prongs 3 and 4 become engaged over the corresponding ends of the shoe in an obvious manner. When the sections are properly in place on the shoe, 90 the hooks or prongs are firmly clasped thereto to resist any outward displacement, and the ears or lugs 5 coöperate to prevent lateral inward displacement. I provide means by which the sections of the anti- 95 slipping device are thereupon fastened against outward lateral displacement, so that their engagement on the shoe is made permanent and secure.

6 designates studs which may be integral 100 with the sections of the anti-slipping attachment, and which project inwardly from the inside edges thereof at points adapted to coöperate most efficiently with the ears or lugs 5 to resist dislodgment or displacement 105 of the sections. In practice I make the studs 6 screw-threaded, and flattened at one or more sides 7 throughout their exposed portions.

8 designates a washer or metallic clip having a hole 9 of an outline corresponding to the transverse section of the stud 6, and

which projects unsymmetrically on one side so as to form an ear or lug on the inside of each of the sections 1 somewhat corresponding to the ears or lugs 5 on the outside thereof.

10 designate nuts which are received upon the threaded studs 6 so as to tightly hold the clips or washers 8 in place.

In use the two sections of the anti-slipping device are applied to a shoe from opposite sides thereof, being slid laterally into place until they fit upon and cover its lower surface. The clips or washers 8 are then applied so as to project inward and coöperate with 15 the ears or lugs 5, after which the nuts 10 are tightened in place. The anti-slipping attachment is then complete for use, being secured against dislodgment in every direction, and particularly forwardly and rearwardly 20 on the shoe, in which directions it is, of course, subject to the most severe strains. While this anti-slipping attachment is adapted for use under all conditions, it is particularly applicable to storms and icy pavements in winter when it is found practically impossible to have horses rough shod at very short notice. Under these circumstances my anti-slipping attachment is particularly useful, being always available and applicable 25 at a moment's notice to any ordinary horse-shoe.

What I claim is:

1. An anti-slipping attachment for horse-shoes, comprising two independent sections, 30 each adapted to slide on the shoe from the sides thereof, and forming together an outline corresponding to the complete bottom area of the shoe, each section having means

rigidly formed at the ends thereof for engaging over the ends of the shoe, and means for 40 holding the sections against lateral displacement.

2. An anti-slipping attachment for horse-shoes, comprising two independent sections forming together an outline corresponding to 45 the complete area of the bottom of the shoe, said sections being elongated slightly at each end, and having rigid inwardly deflected prongs or hooks to engage over the ends of the shoe and removable means holding said 50 sections against lateral displacement.

3. An anti-slipping attachment for horse-shoes, comprising two separate sections each having hooks or prongs, and rigid screw-threaded studs of non-circular transverse 55 section, unsymmetrical washers or metallic clips received over said studs to engage the shoe, and nuts received on said studs to hold said clips or washers in place.

4. An anti-slipping attachment for horse-shoes, comprising two separate sections each having rigid hooks or prongs to engage the shoe, and having rigid screw-threaded studs on their inside edges flattened on two diametrically opposite sides, unsymmetrical 60 washers or metallic clips having holes corresponding in outline with the transverse section of said studs, and nuts received on said studs to hold said washers or clips against the shoe.

In witness whereof, I subscribe my signature, in the presence of two witnesses.

ARTHUR A. HILL.
